(57) **CLAIM**

The ornamental design for an archery sighting device as shown and described.

DESCRIPTION

FIG. 1 is a front perspective view of an archery sighting device showing my new design;

FIG. 2 is a rear elevation view of the invention illustrated in FIG. 1.

FIG. 3 is a right elevation view of the invention shown in FIG. 1;

FIG. 4 is a top plan view of the invention illustrated in FIG. 1;

FIG. 5 is a left elevation view of the invention illustrated in FIG. 1;

FIG. 6 is a front elevation view of the invention illustrated in FIG. 1;

FIG. 7 is a bottom plan view of the invention illustrated in FIG. 1; and

FIG. 8 is a front perspective view of the invention illustrated in FIG. 1 showing my new design interconnected to a riser of a bow, the broken lines representing environment and forming no part of my claimed design.

The broken lines are for illustrative purposes only and form no part of the claimed design.
